United States Patent Office.

CHARLES OSBORNE, OF BROOKLYN, ASSIGNOR TO WHITING MANUFACTURING COMPANY, OF NEW YORK, N. Y.

Design No. 3,656, dated September 7, 1869.

DESIGN FOR A SPOON OR FORK-HANDLE.

The Schedule referred to in these Letters Patent and making part of the same.

To all whom it may concern:

Be it known that I, CHARLES OSBORNE, of Brooklyn, of the county of Kings, and State of New York, have invented a new and original Design for Spoons and Forks; and I do hereby declare that the following is a full, clear, and exact description thereof, which will enable others skilled in the art to make and use the same, reference being had to the accompanying drawings, forming part of this specification.

This invention relates to a new ornamental design for the handles of spoons and forks, such as are made of metal and struck up in dies.

Figure 1 represents the obverse face, and

Figure 2, the reverse face of a spoon, the handle of which is shaped according to my new design, which consists of the flanges *a*, raised from the surface on

both sides at the edge, and arch-shaped at the top, the columns or ribs *b* resting on the capital *c*, and supporting other capitals, *d*, surmounted by planes *e*, with borders arch-shaped at the top, and the keystone *f*, common to both arches.

Having thus described my invention,

I claim as new, and desire to secure by Letters Patent—

The design for the handles of spoons and forks, herein set forth and shown.

The above specification of my invention, signed by me, this 30th day of July, 1869.

CHARLES OSBORNE.
